UNITED STATES PATENT OFFICE.

ANTONIO PAPINI, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

SWITCH AND CONTACT MECHANISM FOR ELECTRIC-CURRENT-REGULATING PLUGS AND SOCKETS.

1,342,061.

Specification of Letters Patent.

Patented June 1, 1920.

Application filed March 29, 1920. Serial No. 369,663.

To all whom it may concern:

Be it known that I, ANTONIO PAPINI, a subject of the King of Italy, having resided in the United States one year last past and having declared my intention of becoming a citizen thereof, residing in the city and county of Philadelphia, State of Pennsylvania, have invented a new and useful Switch and Contact Mechanism for Electric-10 Current-Regulating Plugs and Sockets, of which the following is a specification.

My invention consists of a novel construction of a switch and contact mechanism for an electric regulating plug and socket 15 wherein I employ a porcelain body having a portion thereof flattened and adapted to support a plate or bracket carrying two pins secured thereto, one of said pins being adapted to serve as a journal or a bearing 20 for the switch operating mechanism, and the other of said pins serving as a stop pin to limit the extent of movement of the contact lever or its finger when the latter reaches either of its extreme positions.

It further consists in a novel manner of assembling the contact lever and its adjuncts, and in a novel arrangement of a tension device intermediate of said contact lever and the shank of the insulating key, 30 whereby a proper tension is at all times imparted to the contact lever, according to requirements.

It further consists of a novel manner of assembling the porcelain body portion, the 35 plate carried thereby to which a plurality of pins are secured, the contact lever, the operating spindle which carries said lever and the means for creating a tension upon said contact lever, whereby said parts can be 40 readily assembled or disconnected for the purpose of inspection, replacement and repair.

For the purpose of illustrating my invention, I have shown in the accompanying 45 drawings one form thereof which is at present preferred by me, since the same has been found in practice to give satisfactory and reliable results, although it is to be understood that the various instrumentalities of 50 which my invention consists can be variously arranged and organized and that my invention is not limited to the precise ar-

rangement and organization of these instrumentalities as herein shown and described.

Figure 1 represents a side elevation of an 55 electric current regulating plug and socket, switch and contact mechanism embodying my invention, the outer casing thereof and its adjuncts being shown in section.

Fig. 2 represents a top view of Fig. 1 60 with the top of the inclosing case removed.

Fig. 3 represents on an enlarged scale a section on line 3—3 Fig. 1.

Similar numerals of reference indicate 65 corresponding parts in the figures.

Referring to the drawings.

1 designates my novel construction of switch and contact mechanism, the same comprising the body 2 of porcelain or similar material having the flattened portion 3 70 on which the plate or bracket 4 of brass or other material is fastened.

5 designates the socket or lamp holder, and 6 the case inclosing the operative elements, said case having the flanged top 7 on 75 which the cover 8 is spun or otherwise secured, thereby forming a compact and cheaply assembled device, said case having an annular lower row of holes 9 therein, and said cover having also a row of holes there- 80 in, as indicated at 10.

The bracket 4 has the central disposed pin 11 and the stop pin 12 firmly riveted or secured thereto, as will be understood from Fig. 3.

13 designates a squared shank spindle, 85 which is rotatably mounted on the pin 11, said spindle carrying the contact lever 14 which is rotated in unison with said spindle and terminates at one side in the finger 15, 90 and at the opposite side in the closed curved slot 16, it being apparent that the contact of the opposite termini of said slot with said stop pin 12 will limit the extreme movement of the contact lever 14 within predetermined limits.

The spindle 13 can rotate freely upon the pin 11 as a bearing and is provided with the terminal flange 17, which bears against the bracket or plate 4.

18 designates a portion of the electric current conveyer or plate, which projects through the porcelain body 2, as will be understood from Figs. 1 and 3, with which

the outer end of the finger 15 of the contact plate contacts, the latter having an inwardly deflected portion or foot 19 (see Fig. 3) which rides on the plate 4 which is held in 5 position on the body 2 by any suitable means as the lips or deflected flanges 20, said foot assisting to properly position the contact lever at all times.

21 designates a hole through the cover 6, 10 through which the shank 22 of the insulating key 23 is inserted, said shank having the circular groove 24 therein, which receives the key retaining plate 25 which may be fork shaped or bifurcated if desired and has 15 its outer ends bearing on the contiguous inner surface of the case 6 as will be understood from Fig. 3.

The inner end of the shank 22 has the counter bore or recess 26 therein, in which 20 one end of the coil spring 27 is housed, the opposite end of said spring bearing on the contact arm 14, so that the finger 15 of the latter is always constantly pressed against the contiguous surfaces of the electric conductor 18, thereby insuring an uninterrupted 25 flow of current to the desired point and a smooth operation of the various moving parts.

Such other parts of my novel device as 30 has not been more particularly referred to are of the usual construction and their function and manner of operation will be readily apparent to those skilled in the art.

It will be seen from the foregoing that 35 the bracket or plate 4 can be readily assembled with respect to the porcelain body 2 by means of the lips or flanges 20 and that the contact lever 14 can be readily assembled with respect to the spindle 13, 40 which latter has its bearing upon the central pin 11 and the contact of the stop pin 12 with the upper and lower terminals of the slot 16 will limit the movements of the finger 15 within predetermined limits as is 45 evident, and when the device is assembled as seen in Fig. 3, it will be apparent that the tension of the spring 27 will cause the foot 19 and the finger 15 to properly contact with their contiguous elements, the free 50 end of the finger 15 particularly contacting with the conveyer 18 in a proper manner. The rotation of the key 23 will actuate the contact finger 15 to the desired extent with respect to the conductor or conveyer 18, as is 55 evident.

When the device is assembled the moving elements in the case 6 are effectively housed therein and so are rendered inaccessible and prevented from disintegration in handling 60 or moving the device.

The principal elements of my device can be readily stamped, punched, or pressed out of sheet metal and can be readily assembled without the employment of skilled labor, as 65 is evident.

It will now be apparent that I have devised a novel and useful construction of switch and contact mechanism for electric current regulating plug and socket which embodies the features of advantage enumerated as desirable in the statement of the invention and the above description, and while I have, in the present instance, shown and described a preferred embodiment thereof which will give in practice satisfactory and 70 reliable results, it is to be understood that the same is susceptible of modification in various particulars without departing from the spirit or scope of the invention or sacrificing any of its advantages. 80

Having thus described my invention what I claim as new and desire to secure by Letters Patent, is:—

1. In a device of the character stated, an insulating body having a flattened wall, a 85 plate secured thereto, a bearing pin secured to said plate, a shank having its bearing on said pin, a contact lever mounted on said shank, a key engaging said shank, tension devices intermediate said key and contact 90 lever, and means for limiting the movements of the latter.

2. In a device of the character stated, a body, a plate secured thereto and having a bearing pin and a stop pin secured thereto, a 95 shank rotatably mounted on said bearing pin, a contact lever rotatable in unison with said shank and having a finger at one end, and a curved slot at the other end coacting with said stop pin, and a key in engagement with said shank for rotating the latter and said contact lever. 100

3. In a device of the character stated, a body having a flattened wall, a plate secured to said wall and having a bearing pin and 105 a stop pin secured thereto, a shank rotatably mounted on said bearing pin, a contact lever rotatable in unison with said shank and having a finger at one end, and a curved slot at 110 the opposite end, the walls of said slot engaging said stop pin, a key in engagement with said shank, and tension devices intermediate said key and contact lever.

4. In a device of the character stated, an insulating body having a flattened wall, a 115 plate secured thereto, a bearing pin secured to said plate, a squared shank having its bearing on said pin and provided with a terminal flange bearing on said plate, a contact lever mounted on said shank, a key engaging said shank, a spring interposed between the inner end of said key and said contact lever, and means for limiting the movement of said contact lever. 120

5. In a device of the character stated, an 125 insulating body, having a flattened wall, a plate secured thereto, a bearing pin projecting from said plate, a squared shank having its bearing on said pin and provided with a terminal flange bearing on said plate, an 130

- electric conveyer projecting through said body, a contact lever carried by said shank and having a finger engaging said conveyer, an inwardly deflected foot on said lever riding on said plate, a key engaging said shank, a case inclosing said body, and means common to said key and case for retaining said key in position.
6. In a device of the character stated, an insulating body having a flattened wall, a plate secured thereto, a bearing pin projecting from said plate, a squared shank having its bearing on said pin and provided with a terminal flange bearing on said plate, an electric conveyer projecting through said body, a contact lever carried by said shank and having a finger engaging said conveyer, an inwardly deflected foot on said lever riding on said plate, a key engaging said shank, a case inclosing said body, and means common to said key and case for retaining said key in position, in combination with a coil spring surrounding said shank and located between said key and contact lever.
10. 7. In a device of the character stated, an insulating body having a flattened wall, a plate secured thereto, a bearing pin projecting from said plate, a squared shank having its bearing on said pin and provided with a terminal flange bearing on said plate, an electric conveyer projecting through said body, a contact lever carried by said shank and having a finger engaging said conveyer, an inwardly deflected foot on said lever riding on said plate, a key engaging said shank, a case inclosing said body, and means common to said key and case for retaining said key in position, in combination with a coil spring surrounding said shank and located between said key and contact lever.
15. 8. In a device of the character stated, an insulating body having a flattened wall, a plate secured thereto, a bearing pin projecting from said plate, a squared shank having its bearing on said pin and provided with a terminal flange bearing on said plate, an electric conveyer projecting through said body, a contact lever carried by said shank and having a finger engaging said conveyer, an inwardly deflected foot on said lever riding on said plate, a key engaging said shank, a case inclosing said body, and means common to said key and case for retaining said key in position, in combination with a coil spring surrounding said shank and located between said key and contact lever.
20. 9. In a device of the character stated, an insulating body having a flattened wall, a plate secured thereto, a bearing pin projecting from said plate, a squared shank having its bearing on said pin and provided with a terminal flange bearing on said plate, an electric conveyer projecting through said body, a contact lever carried by said shank and having a finger engaging said conveyer, an inwardly deflected foot on said lever riding on said plate, a key engaging said shank, a case inclosing said body, and means common to said key and case for retaining said key in position, in combination with a coil spring surrounding said shank and located between said key and contact lever.
25. 10. In a device of the character stated, an insulating body having a flattened wall, a plate secured thereto, a bearing pin projecting from said plate, a squared shank having its bearing on said pin and provided with a terminal flange bearing on said plate, an electric conveyer projecting through said body, a contact lever carried by said shank and having a finger engaging said conveyer, an inwardly deflected foot on said lever riding on said plate, a key engaging said shank, a case inclosing said body, and means common to said key and case for retaining said key in position, in combination with a coil spring surrounding said shank and located between said key and contact lever.
